AEROPLANE

Walter W. Rothenhoefer, St. Louis, Mo.

Application August 19, 1935, Serial No. 36,786

3 Claims.

(Cl. 244—17)

My invention relates to improvements in aeroplanes and the main object is to provide an improved supporting and sustaining means for aeroplanes of the general type known as helicopters and designed to permit vertical ascent and descent.

Another object is to provide in a helicopter type supporting means a rotor having elongated blades and means for increasing the lift or vertical thrust of these blades during any part of their rotation or orbital movement whereby the aeroplane may be tilted forwardly, rearwardly or laterally to guide the aeroplane in horizontal flight.

Another object is to provide a helicopter type supporting means comprising a rotor made up of a plurality of elongated airfoils or winglike blades and means at the outer ends thereof for varying the cross sectional shape or area of the blades at periodic intervals during their orbital motion and any points around the circumference thereof whereby the lift will be periodically increased to guide and control the flight of the aeroplane.

Another object is to provide novel and positive means for controlling both the degree and the horizontal position of the aforesaid increased lift of the blades.

With these and other objects in view the invention resides in the novel construction and arrangement of parts as hereinafter fully set forth and claimed, reference being had to the accompanying drawings wherein:

Figure 1 is a side elevation of an aeroplane constructed in accordance with my invention.

Figure 2 is a plan view.

Figure 3 is an enlarged cross section through the fuselage and rotor of the aeroplane shown in Figure 1.

Figure 4 is a horizontal section through the rotor along the line 4—4 in Figure 3.

Figure 5 is a section along the line 5—5 in Figure 3.

Figure 6 is an enlarged perspective view of one of the cam plungers alone.

Figure 7 is a section along the line 7—7 in Figure 3.

Figure 8 is an enlarged longitudinal section through the outer end portion of one rotor blade showing the adjustable member as adjusted to increase the lift of the blade.

Figure 9 is an inverted plan view of the structure shown in Figure 8.

Figure 10 is a cross section along the line 10—10 in Figure 8.

Figure 11 is an inverted plan view similar to Figure 9 but showing a modified form of lift adjusting member.

Figure 12 is a cross section through the outer end portion of the blade shown in Figure 11.

Figure 13 is an enlarged section along the line 13—13 in Figure 3 showing one rotor blade tilted upward at its leading edge.

Figure 14 is a similar view showing the position of the parts when the rotor blade is tilted upward at its trailing edge.

Referring now with more particularity to the drawings my invention comprises a rotor designated generally at 10 mounted above the fuselage 11 of the aeroplane or substantially the center of gravity of the structure. The rotor comprises a hub drum 12 secured at 13 atop a drive shaft 14 which extends vertically up through the upper surface 15 of the fuselage and is driven by a conventional engine E located in any suitable position. As herein shown the engine E is of the air cooled radial type placed in the nose of the fuselage 11 and connected to the drive shaft 14 through a propeller shaft 16 and gears 17. A clutch (not shown) of any suitable kind may be used in the shaft 16. Some distance below the drum 12 the drive shaft 14 is supported and journaled through a bearing block 18 which is rigidly mounted above the fuselage 11 by a streamlined turret 19 as shown. Also at the point where the drive shaft 14 enters the upper fuselage surface 15 the shaft is placed through a thrust bearing 20 secured at 21 to the fuselage.

The hub drum 12 has an annular upstanding wall 22 turned inward to form an annular mounting flange 23 at its upper end and a circular mounting plate 24 is screwed at 25 to this flange 23.

Four rotor blades or wings 26, 26a, 26b and 26c are provided and are of any suitable length and chord and are fabricated similar to the usual wing structure of aeroplanes with a framework 27 and covering 28. At their predetermined inner ends the blades are secured to elongated leaf springs 29, 29a, 29b and 29c each made up of several leaves and formed at their inner ends with bearing balls 30.

These blades 26, 26a, 26b and 26c are arranged with their mounting springs 29, 29a, 29b and 29c in crossing overlapping arrangement atop the mounting plate 24 as shown in Figure 4 and are mounted in such position by four bearing blocks 31 secured at 32 to the mounting plate 24 and having rounded sockets 33 receiving the bearing 34.

balls 30 at the ends of the springs. The blades thus extend radially but eccentrically from the rotor 10, that is each opposed pair of blades are axially parallel but not in exact alignment even though the structure as a whole is nicely balanced as will be understood. Through the ball mounting of their inner ends the blades may swing upwardly and downwardly at their free ends and may also twist or turn on their axes. 5

10 Adjacent the point where each spring 29, 29a, 29b and 29c extends from the rotor 10 inverted U-shaped brackets or shackles 34 are set astraddle the springs and secured at 35 to the mounting plate 24 to limit the aforesaid upward and downward swinging of the blades at their free ends. 15 Rocker plates 36 are secured on the upper and lower faces of the springs where they pass through the brackets 34 and viewed from the ends these plates 36 are of wide V-shape with their apices 20 37 turned outward from the said faces of the springs whereby diverging angular faces 38 are formed running out to the lateral margins of the springs. Pressure blocks 39 are slidably keyed at 40 in the parallel vertical legs 41 of the brackets 34 and are normally urged upward against the lower rocker plates 36 by expansion coil springs 42 braced between the pressure blocks and the adjacent supporting plate 24. Thus the 25 springs 29, 29a, 29b and 29c are normally and 30 resiliently urged upward against the bights 43 of the brackets 34 and due to the shape of the angular faces 38 of the rocker plates 36 the blades will stand not in a true horizontal plane but at an angle to the horizontal so that the blades will 35 tilt upwardly either at their intended leading edges 44 or their trailing edges 45 as shown in Figures 13 and 14. At the same time the blades may swing upward or downward within limits at the free ends as described due to the resiliency 40 of the springs 29, 29a, 29b and 29c and of their mounting through the brackets 34.

The structure as so far recited is complete in that rotation of the blades 26, 26a, 26b and 26c is calculated to raise and sustain the aeroplane in flight. The normal direction of rotation for this purpose is indicated by the several arrows in the drawings and of course the leading edges 44 of the blades move forwardly around the orbital path of the blades. During this rotation the air pressure on the blades tends to rock them back on their axes so that the said leading edges 44 are tilted upwardly (Figure 13). Now should the engine E fall the pilot may disengage the rotor from the engine allowing the rotor to turn free. The natural result of the falling of the plane thus brought about is to reverse the direction of rotation of the rotor blades 26, 26a, 26b and 26c and the air pressure thus being reversed on the blades rocks them back so that their trailing edges 45 are inclined upwardly and now an upward thrust is again provided by the blades tending to lower the aeroplane slowly and safely to the ground. This is the purpose and function of the rocker supports for the blades in the brackets 34. 55

60 To guide the aeroplane in horizontal flight I provide means for varying the lift or upward thrust of the blades 26, 26a, 26b and 26c during any part of their orbital path or movement as 65 will now be described.

60 As shown in Figures 8, 9 and 10 substantially triangular flexible and resilient flaps or leaves 46 are secured to the undersides of the blades 26, 26a, 26b and 26c adjacent the trailing edges and 75 outer ends thereof. These leaves 46 are prefer-

ably made of some flat spring metal and are secured by screws or rivets 47 to the framework 27 of the blades leaving the trailing edges 48 and inner edges 49 of the leaves free. Normally the leaves then lie flat beneath the blades to offer 5 no obstruction to the air. Bell crank pressure levers 50 are fulcrumed at 51 within the outer ends of the blades and have pressure feet 52 which bear on the free corners of the leaves 46 but which are normally held upward by retractile 10 coil springs 53 stretched between the pull arms 54 of the levers 50 and screw eyes 55 affixed within the wings as shown. Operating cables 56 are secured to these pull arms 54 and extend inward longitudinally through the blades through bearing sleeves 57 in the framework 27 and finally emerging from the inner ends of the blades near the trailing edges 45 thereof and led across the drum 12. It will be readily understood that a 15 pull on these cables 56 swinging the pressure feet 20 52 of the bell crank levers 30 downward will spring or flip the free corners of the leaves 45 downward as shown in Figures 8 and 10 and the obstruction thus offered to the air flow beneath the blades will result in a great increase in the 25 lift afforded by the blades in well known manner. At their inner ends the cables 56 are secured to bell crank operating levers 58 which are fulcrumed between bearing ears 59 near the center of the mounting plate 24 and each having 30 a draw arm 60 disposed in line with its associated cable to which it is attached at 61. These bell crank levers 58 are placed through slots 62 in the said plate 24 and the legs 63 drop down into the drum 12 where they are pivotally connected 35 at 64 to push rods 65 slidably mounted vertically at 64 to push rods 65 slidably mounted vertically through guides 66 in the bottom of the drum. Sufficient play is provided in the connections 64 to allow the push rods when urged upwardly to swing the levers 58 and exert a pull on the cables 40 56 and flex the leaves 46 downward as described. 45 Of course each cable 56 has its own operating lever 58 and separate push rods 65 are provided for each lever, the said push rods being evenly spaced and dropping down into contact with the upper end face of the bearing block 18 supported in the turret 19. The lower ends of these push rods 65 carry rollers 67 as shown.

A cam mechanism and operating means are provided for operation of the push rods 65 comprising four hydraulic cylinders 68 secured up 50 into the lower end of the bearing block 18 in alignment with the push rods and equally spaced fore and aft and laterally relative to the line of flight of the aeroplane. Pistons 69 are slidably 55 mounted in the cylinders 68 and have their piston rods 70 extended upward through apertures 71 in the cylinder ends and aligned bores 72 in the bearing blocks. Arcuate cam heads 73 are rigidly attached to the upper ends of the piston rods and normally rest in enlarged sockets 74 at the upper ends of the bores 72 so that the rounded upper or working edges 75 of the cam heads normally stand flush with the upper end face of the bearing block 18. In this position 60 the push rods 65 run free without any upward or downward movement but when any one of the cam heads 73 is projected upwardly the push rods as they run around over the rounded edges 75 thereof will be first raised and then dropped 65 downward again resulting in a pull on the cables 56 and the flexing of the leaves 46 downward during a short portion of the travel of each blade 26, 26a, 26b and 26c. When the cam heads 73 drop downward into their sockets 74 the parts 75

return to normal position of their own weight and under influence of the air pressure on the leaves 46 and the pull of the springs 53 on the bell crank pressure levers 50 as will be understood.

The pistons 69 are urged upwardly as described by the pressure beneath of hydraulic fluid in the cylinders 68, this fluid being carried separately to each cylinder by lines 76 through the lower 10 end caps 77 of the cylinders as shown. These lines 76 pass downwardly within the turret 19 and alongside one wall of the fuselage 11 to four driver cylinders 78 arranged in equally spaced relation about the control stick 79 and supported 15 on a ring 80 and bracket 81. The said control stick 79 may be swung forwardly, rearwardly or to either side by its ball and socket mounting 82 and is connected by a spider 83 to the piston rods 84 of the pistons 85 in the cylinders 78 so that 20 when the stick is moved by the pilot toward any cylinder the piston therein forced out the hydraulic fluid under pressure and exerts an equal pressure in the corresponding cylinder 68 and moves the piston 69 therein an equal distance. 25 This of course makes it possible for the pilot by manipulation of the control stick 79 to move any of the cam heads 73 upward and so vary the side or place during the orbital rotation of the blades 26, 26a, 26b and 26c where the lift of these blades 30 is increased by flexing the leaves 46 downward as described.

This controllable and variable lift of the blades act to guide the aeroplane during flight as will now be described. Assuming that the 35 aeroplane has risen horizontally from the ground to the desired height and the pilot desires to fly forwardly in a horizontal line, he simply pushes the control stick 79 in the proper direction (preferably forwardly but depending on the 40 hookup of the cylinders 88 and 78) and the cam head 73 at the rear of the drive shaft 14 is elevated into the path of the push rods 65. Now as the blades 26, 26a, 26b and 26c rotate carried 45 around by the drum 12 these push rods 65 as they pass over the raised cam head will be raised and then dropped downward as described hereinbefore. This results in the leaves 46 being flexed downward each time a blade passes through the 50 rear portion of its orbital path and the lift or upward thrust of the rotor blades is thus increased at the rear tilting the aeroplane upwardly at the rear and gliding it forwardly. By nicely adjusting this lift by the position of the control stick 79 a balance can be obtained at 55 which the aeroplane will glide forwardly at substantially even keel meanwhile being sustained in the air by the whirling blades. The same action may be employed to guide the aeroplane off to the side or even to the rear by suitable manipulation of the stick 79 and by moving the "lift" around the path of the blades as will be understood. In lieu of the leaves 46 at the outer ends of the blades 26, 26a, 26b and 26c swinging or hinged flaps or leaves 86 may be employed and 60 pivotedly mounted at 87 be arranged by a pull on the cables 56 to swing rearward and increase the chord of the blades at that point and hence increase the lift. The blades may be cut away at

their trailing edges as shown at 88 and the leaves 86 then arranged to refill this space when the cables are pulled. Springs 89 normally swing the leaves 86 forwardly clear of the space 88 as shown. It will be evident that to increase the 5 lift of the blades the small amount necessary a very slight movement of the leaves 46 or 86 is needed and also that the increase in lift may be obtained in a number of ways that is by varying the area of the blade, by varying the cross section 10 shape or by a combination of both and all are considered within the scope of my invention.

The mounting plate 24 and the parts mounted therein are enclosed by an inverted cup-shaped cover 90 which is screw threaded at 91 down 15 over the upper margin of the wall 22 of the drum 12 and has openings 92 to clear the springs 29, 29a, 29b and 29c as well as bearing sleeves 93 clearing the cables 56.

While I have herein set forth a certain preferred embodiment of my invention, it is understood that I may vary from the same in minor structural details, so as best to construct a practical device for the purpose intended, not departing from the spirit of the invention and within 20 the scope of the appended claims.

I claim:

1. In a rotor for helicopters, a rotatable hub member, blades extended radially from the hub member, a bearing block beneath the hub member, cams arranged in the bearing block at spaced points around a circle having as its axis the axis of rotation of the hub member, a flap fastened by one margin to each blade, and control means whereby elevating any one of the said cams will 30 cause a flexing of the flap on each blade as it passes a point in radial alignment with the raised cam to increase the lift of the blade.

2. In a rotor for helicopters, a rotatable hub member, blades extended radially from the hub member, a bearing block beneath the hub member, cams arranged in the bearing block at spaced points around a circle having as its axis the axis of rotation of the hub member, a flap fastened by one margin to each blade, and control means whereby elevating any one of the said cams will 40 cause a flexing of the flap on each blade as it passes a point in radial alignment with the raised cam to increase the lift of the blade, the 45 said control means including push rods depended from the hub member for engagement with the 50 cams, bell crank levers connected to the push rods and flaps, and cables connecting the bell crank levers.

3. In a rotor for helicopters, the same including a rotating hub and a plurality of blades radially extended therefrom, flexible flaps attached to the blades and normally standing flush therewith but capable of being flexed downwardly to increase the lift of the blade, means at the hub 55 for periodically flexing the flap of each blade downwardly as it passes a point around the axis of the rotor, the said means comprising a plurality of cam located around the axis of the rotor, controlling means actuated by the cams and connected to the said flaps, and remotely located 60 means for selectively actuating the said cams.

WALTER W. ROTHENHOFER.
